Mr. H. Campbell,
ATTORNEY.

UNITED STATES PATENT OFFICE

ARTHUR D. LELONG, OF VERONA, NEW JERSEY

PAD SUPPORT

Application filed January 14, 1929. Serial No. 332,352.

This invention relates to a device for holding a pad in which the leaves of the pad are loose and are turned over and back from day to day so as to retain a record of the notations thereon. The pads are usually calendar pads and the invention resides in a holder for the pad which can be easily attached to or detached from a base in which the holder or clip is secured by the resiliency of the clip which is made of spring wire.

The invention is illustrated in the accompanying drawing in which Figure 1 is a perspective view of my improved pad holder with the pad partly broken away to show the spring clip to better advantage and Figure 2 is a perspective view of the spring clip.

The device consists of a suitable base 10 which is of any desired form and is usually made of sheet metal and has ears 11 struck up therefrom or the ears can be attached when made of a separate piece. They are shown in the drawing as being inwardly directed although the position can be reversed and they extend toward the outer edges of the base.

The spring clip comprises a piece of wire that is formed with arms 12 which extend into hair-pin shaped portions 13, the end arms 14 of which are arranged to pass through holes 15 provided in the pad 16 of the usual form. The ends of the arms 14 are seated in recesses 17 that are punched in the top face of the base, although these depressions 17 can be dispensed with. The arms 12 extend upwardly as at 18 and are connected by a cross-arm 19.

In assembling the pad and the holder the pad is slipped on to the arms 14 then the arms 12 are squeezed toward each other, seated under the lips 11 and then released. The parts are thus held in position and the arm 19 or the cross-arm acts as a rest for the leaves of the pad which are turned over as shown at 20 in the dotted outline in Figure 1.

The top sheet of the pad 16 is usually made of stiff cardboard to act as a support underneath the leaves of the pad as they are turned over. It will be noted that the clip not only forms a device for holding the pad in position but also for supporting the turned

over leaves and for maintaining the clip on the base.

I claim:—

1. A pad support comprising a base with opposed lips on its top face, a wire clip having its central portion formed of side arms that engage the lips by lateral resiliency and having its two ends raised forming on one end hair-pin portions for engaging a pad and on the other end including a raised cross-bar to support raised leaves of the pad.

2. In a pad support, a clip formed of wire bent to provide side arms substantially parallel, the wire extending upwardly from one end of the side arms and joined by a cross arm and extending upwardly from the other end of the side arms and formed into hair-pin portions to hold a pad.

In testimony whereof I affix my signature.

ARTHUR D. LELONG.
